[57] CLAIM

The ornamental design for musical tone controller, as shown and described.

DESCRIPTION

FIG. 1 is a front elevational view of a musical tone controller showing my new design;

FIG. 2 is a right-side view thereof;

FIG. 3 is a top plan view thereof;

FIG. 4 is a bottom plan view thereof;

FIG. 5 is a rear view thereof; and,

FIG. 6 is a front perspective view thereof.

The broken lines are shown for illustrative purposes only and form no part of the claimed design. The cable is fragmentarily shown to indicate indeterminate length.
